[57] **CLAIM**

The ornamental design for a faucet, as shown and described.

DESCRIPTION

FIG. 1 is a front perspective view of a faucet showing our new design;

FIG. 2 is as rear perspective view thereof;

FIG. 3 is a front elevational view thereof;

FIG. 4 is a rear elevational view thereof;

FIG. 5 is a top plan view thereof;

FIG. 6 is a left side elevational view thereof;

FIG. 7 is a cross-sectional view of the spout taken along line 7—7 is FIG. 6;

FIG. 8 is a right side elevational view thereof;

FIG. 9 is a bottom plan view thereof;

FIG. 10 is a rear perspective view of a second embodiment of the faucet;

FIG. 11 is a left side elevational view of the embodiment of FIG. 10;

FIG. 12 is a cross-sectional view of the spout of said second embodiment taken along line 12—12 in FIG. 11; and,

FIG. 13 is a front elevational view of FIG. 11.

The broken line showings of the aerator and handle in FIG. 1 are for purposes of illustration only and form no part of the claimed design.
